(57) **CLAIM**

The ornamental design for a display screen with graphical user interface as shown and described.

DESCRIPTION

FIG. 1 is a front view of a display screen with graphical user interface according to the claimed design, with the display screen shown on a monitor.

FIG. 2 is a rear view of the monitor.

FIG. 3 is a left side view of the monitor.

FIG. 4 is a right side view of the monitor.

FIG. 5 is a top view of the monitor; and,

FIG. 6 is a bottom view of the monitor.

The dash-dash broken lines in the drawings illustrate portions of the display screen, portions of the graphical user interface, and environmental matter that form no part of the claimed design.

The dash-dot broken lines in the drawings define the bounds of the claimed design and form no part thereof.

1 Claim, 6 Drawing Sheets
